UNITED STATES PATENT OFFICE.

JOHN J. LANE, OF ST. LOUIS, MISSOURI.

VALVE.

1,290,587.

Specification of Letters Patent.

Patented Jan. 7, 1919.

Application filed January 29, 1918. Serial No. 214,308.

To all whom it may concern:

Be it known that I, JOHN J. LANE, a citizen of the United States, residing at St. Louis, Missouri, have invented a certain new and useful Improvement in Valves, of which the following is a full, clear, and exact description, such as will enable others skilled in the art to which it appertains to make and use the same.

10 This invention relates to valves, and particularly to valves of the type shown in my prior U. S. Patent No. 1,225,974, granted to me on the 15th day of May, 1917, wherein the stem of the valve is provided with a cone-shaped portion that projects upwardly into a tapered seat in the bonnet of the valve, so as to prevent leakage around the portion of the stem that projects upwardly through the top of the bonnet.

15 20 The main object of my present invention is to provide a valve of the character referred to, in which the cone-shaped portion and tapered seat that prevent leakage around the valve stem are augmented or safe-guarded by the provision of an independent leak-preventing means that is actuated by the pressure of the fluid in the valve.

Another object is to provide a packless valve of the general type referred to that is 30 equipped with the usual leak-preventing means and also with an independent, removable means for preventing leakage around the valve stem in case the first mentioned means becomes inoperative. Other objects 35 and desirable features of my invention will be hereinafter pointed out.

Figure 1 of the drawings is a vertical sectional view of a valve constructed in accordance with my invention; and

40 Fig. 2 is a horizontal sectional view, taken on the line 2-2 of Fig. 1.

Referring to the drawings which illustrate the preferred form of my invention, A designates the valve casing or body, B the 45 usual bonnet that is threaded into the upper portion of the body, and C designates the valve proper which co-operates with a horizontal valve seat 1 in said body. The valve C is carried by a member 2 that is vertically movable in the bonnet and which is provided with V-shaped ribs 3 that co-operate with correspondingly shaped grooves 4 formed in the lower portion of the bonnet B to prevent rotary movement of said member. The 50 valve stem D is in threaded engagement with the member 2 so as to move the valve C to-

ward or away from its seat, as desired, by rotation of said stem.

The stem D is provided intermediate its ends with an enlarged conical portion 6 that projects upwardly into a tapered seat 7 formed in the bonnet B, said portion 6 being forced upwardly into its seat by a coiled expansion spring 8 interposed between a shoulder 9 in the bonnet and an abutment 10 on the valve stem D and also by the upward pressure which the medium controlled by the valve exerts on the conical portion 6.

I have found in practice that the conical portion 6 and co-operating tapered seat 7 do not always perform their intended function, this being due to several causes, some of which are,—the lodgment between the co-operating surfaces of particles of foreign matter, poor or faulty grinding in of these surfaces, and weakening or breakage of the spring that holds said surfaces in contact. In order to overcome this defect present in the packless valves of this particular type heretofore in use, I have devised a construction wherein an additional sealing means is provided which operates in conjunction with, but entirely independent of, the conical sealing means just described.

In the embodiment of my invention herein shown, the means I prefer to use to doubly seal the valve stem consists of a resilient or flexible disk E arranged on the valve stem which co-operates with an annular seat 11 formed in the bonnet B adjacent the conical surface 7. The disk E is provided with an opening 12, preferably non-circular, that fits over a correspondingly-shaped portion 13 on the valve stem immediately under the enlarged conical portion 6. The disk E is free to move vertically relatively to the portion 6 and is retained in operative position on said stem by any suitable means, the means herein shown consisting of a circular piece of wire 14 that is sprung into a groove 15 under said disk. By the simple means just described the disk is held securely in operative position on the valve stem D, but can be readily removed for replacement by simply removing the spring wire 14 and slipping the disk off of the valve stem endwise.

As shown in Fig. 1, the disk E is so disposed between the base of the enlarged conical portion 6 and the retaining wire 14 that it is permitted a slight vertical movement 110 on the valve stem, and consequently, can be forced against its seat 11 absolutely inde-

pendent of the conical seating surface 6. In other words, assuming the parts 6 and 7 to be in engagement with each other, and the valve C closed, the disk E will lie on top of the 5 retaining wire 15, and consequently, will be a slight distance away from its seat 11. As soon as the valve C is opened so as to admit a fluid under pressure to the bonnet B, the pressure therein will act to force the disk 10 upwardly against its seat and against the base of the conical portion 6, thus preventing any of the fluid from escaping around the valve stem. It is obvious that should the conical portion 6 and its coöperating 15 seat 7 not engage properly at any time, due to various reasons heretofore mentioned, the pressure of the medium that passes through the valve will automatically seat the disk E, and thus effectively prevent any leakage of 20 fluid around the valve stem. It is also obvious that when the valve C is in its extreme open position, the upper edge of the member 2 will engage the disk and positively force it into engagement with its seat, thus further insuring a tight joint.

I prefer to form the disk E of fiber or vulcanite, as these materials can be obtained cheaply and are possessed of the desired wearing qualities, flexibility and resiliency, 30 but I do not wish to limit myself to any particular material, as I am aware of various compositions which are equally well adapted for this purpose.

By constructing a valve in the manner 35 above described there is no liability of the fluid that passes through the valve leaking or escaping around the valve stem, as the usual leak-preventing means is augmented by an additional leak-preventing means 40 which operates independently of said first-mentioned means. My improvement can be installed in the valve at a very slight additional expense, is easily applied, and readily detachable for the purpose of renewal.

45 Having thus described my invention, what I claim, and desire to secure by Letters Patent, is:

1. A packless valve having a cone-shaped portion on the stem that projects upwardly 50 into a tapered seat in the valve body for preventing leakage around the valve stem, and additional leak-preventing means independent of said first mentioned means and adapted to be operated by the pressure of 55 the medium which the valve controls.

2. A packless valve, comprising a body portion provided with a bonnet that has a tapered seat, a valve, a vertically-movable member in said body portion to which the 60 valve is connected; a stem for operating said member, a cone-shaped portion on said stem that projects upwardly into the seat in the bonnet, a second seat on the bonnet and an auxiliary sealing device loosely mounted on 65 the stem below said cone-shaped portion and

adapted to be forced upwardly against said second seat by the internal pressure in the valve body, said device being so arranged that said vertically-movable member will force said device tightly against its seat 70 when the valve is wide open.

3. In a packless valve, a vertically-movable valve, an operating stem for said valve arranged for rotation in the valve bonnet, a conical portion on said stem that projects 75 upwardly into a tapered seat in said bonnet, means for maintaining said conical portion and seat in engagement with each other, an annular horizontal seat on the bonnet beneath said tapered seat, and a disk movably 80 mounted on said stem and adapted to be forced upwardly against said horizontal seat by the pressure of the medium that the valve controls.

4. In a packless valve of the type having 85 a conical portion on the valve stem that projects upwardly into a tapered seat in the valve body, an annular horizontal seat on the valve body adjacent the tapered seat, and a member movably mounted on the valve 90 stem and adapted to be forced upwardly against said horizontal seat by the pressure of the medium in the valve body.

5. In a packless valve of the type having 95 a conical portion on the valve stem that projects upwardly into a tapered seat in the valve body, an annular horizontal seat on the valve body adjacent the tapered seat, and a member loosely mounted on said valve stem that is adapted to be forced upwardly 100 against said horizontal seat by the pressure of the medium controlled by the valve.

6. In a packless valve of the type having a conical portion on the valve stem that projects upwardly into a tapered seat in the 105 valve body, an annular horizontal seat on the valve body adjacent the tapered seat, and a resilient member movably mounted on said valve stem and adapted to be forced upwardly against said horizontal seat by the 110 internal pressure in the valve body.

7. In a packless valve of the type having a conical portion on the valve stem that projects upwardly into a tapered seat in the valve body, an annular horizontal seat on the valve body adjacent the tapered seat, and a removable member movably mounted on 115 said valve stem that is adapted to be forced upwardly against said horizontal seat by the internal pressure in the valve body.

8. In a packless valve of the type having a conical portion on the valve stem that projects upwardly into a tapered seat in the valve body, an annular horizontal seat on the valve body adjacent the tapered seat, and a 125 flexible member vertically movable on said valve stem that is adapted to be forced upwardly against said horizontal seat by the pressure of the medium controlled by the valve.

9. In a packless valve of the type having a conical portion on the valve stem that projects upwardly into a tapered seat in the valve body, an annular horizontal seat on the valve body adjacent the tapered seat, a non-circular portion on said valve stem, and a disk-shaped member that is adapted to be forced upwardly against said horizontal seat by the pressure of the medium controlled by the valve, said member having a non-circular opening therein that fits over the non-circular portion of said valve stem.
10. In a packless valve of the type having a conical portion on the valve stem that projects upwardly into a tapered seat in the valve body, an annular horizontal seat on the valve body adjacent the tapered seat, a member movably mounted on said valve stem that is adapted to be forced upwardly against said horizontal seat by the pressure of the medium controlled by the valve, and detachable means for retaining said member in operative position.

JOHN J. LANE.
